UNITED STATES PATENT OFFICE.

GEORGE A. RAYMOND, OF ADRIAN, MICHIGAN, ASSIGNOR, BY DIRECT AND MESNE ASSIGNMENTS, TO THE MICHIGAN WOVEN WIRE FENCE CO., OF DETROIT, MICHIGAN.

MACHINE FOR MAKING WIRE FABRIC.

No. 839,033.

Specification of Letters Patent.

Patented Dec. 18, 1906.

Application filed March 27, 1905. Serial No. 252,194.

To all whom it may concern:

Be it known that I, GEORGE A. RAYMOND, a citizen of the United States, residing at Adrian, in the county of Lenawee, State of Michigan, have invented certain new and useful Improvements in Machines for Making Wire Fabric; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to looms for weaving wire fabric, more especially designed for use in the manufacture of wire fencing, the general character of said loom being shown in my copending application, Serial No. 320,161; and the invention consists more particularly in the construction and operation of a duplex telescopic needle, whereby two strands of woof-wires may be woven into the fabric simultaneously and a desirable cross-wrap accomplished, as hereinafter more fully set forth, and pointed out particularly in the claims.

The object of the invention is to provide efficient means for weaving the woof-wires onto the warp-wires and making a cross-wrap of the woof-wires at the completion of each operation of attaching said wires to the warp-wires, the arrangement being such as to enable two warp-wires to be applied simultaneously through the employment of a duplex telescopic needle mounted in the shuttle and actuated as the shuttle passes from strand to strand of the warp-wires in the operation of weaving.

The above object is attained by the mechanism illustrated in the accompanying drawings, in which—

Figure 1 is a fragmentary view in perspective of a portion of a fence-loom, illustrating the application of my invention. Fig. 2 is an enlarged fragmentary view in section as on line 2 2 of Fig. 1. Fig. 3 is a front elevation of Fig. 2, parts being broken away. Fig. 4 is a fragmentary view in section as on line 4 4 of Fig. 2. Fig. 5 is a detail, partly in section, of the duplex telescopic needle, the parts thereof being disassembled. Fig. 6 is a fragmentary view in section as on line 6 6 of Fig.

4. Fig. 7 is an elevation of the wrap formed by the operation of the needle. Fig. 8 is a perspective view of the duplex telescopic needle. Fig. 9 is a longitudinal section through the needle. Fig. 10 is an elevation of one end of the needle, partly in section. Fig. 11 is an elevation of the opposite end of the needle, also partly in section.

The loom or fence-weaving machine, of which a portion only is shown herein to illustrate the application of my invention, is of the rotary type and of the same general construction as that shown and described in my pending application, Serial No. 212,110. The construction and operation thereof will not, therefore, be specifically entered into except so far as may be necessary in describing the operation of my present invention.

Referring to the characters of reference, 1 designates the wheels, which, with the cross-plates 2 connecting them, form the rotary reel or drum upon which the mechanism is carried. Mounted upon said plate are the opposed track members 3, between which the shuttle 4 is guided in its passage across the machine. Upon opposite sides of the cross-plates 2 are the notched posts 5, that receive the warp or longitudinal wires 6, which are fed into the machine in any suitable manner and which draw in a straight line between said posts and lie in the path of the transversely-movable shuttle.

It will be understood that there may be as many of the cross-plates 2 employed as desired in the machine and that there will be a shuttle for each cross-plate and shuttle-track, the shuttles in succession being carried across the longitudinal wires as the machine rotates and returned into position for a succeeding operation in a manner fully set forth in my above-mentioned application. The shuttle is directed from wire to wire of the longitudinal strands by means of the curved track-sections 7, which are rigidly supported in a suitable manner (not shown) by the framework around the machine. The movement of the shuttle is made intermittent because of the divisions in the track 7, into engagement with which the antifriction-roller 8 on the shuttle is carried by the rotary movement of the machine, as partially illustrated in Fig. 1.

The duplex needle mounted in the shuttle

comprises a telescopic shaft consisting of the male section 9 and the female section 10, fitting therein, said female section having a channel 11, which receives the pins 12 in the male section, whereby said parts are caused to register when placed together, so as to bring the longitudinal slots 13 therein in proper alinement and at the same time cause the sections to rotate in unison, while allowing them to reciprocate longitudinally. The slotted needle formed by the telescopic sections is journaled in a hanger 14, forming a part of reciprocatory head 15, mounted to slide between the guides 16, attached to the 15 needle.

Secured to the head 15 is a bracket 17, carrying an antifriction-roller 18, which as the machine revolves is adapted to engage the oppositely-disposed track members 19 and 20. Said track members 19 and 20 are so positioned and are of such shape that when the movement of the machine causes the roller to engage the track member 19 the head 15 will be moved between the guides, so as to throw the slotted needle into the notches 21 in the track members 3 along which the shuttle travels, causing said needle to receive in the longitudinal slot therein the warp-strand 6 of the fabric which stands directly over the notches in said track members, whereby the wire is embraced by the needle and caused to lie at the center of its axis of rotation, in which position the needle is rotated, as hereinafter explained, to wrap the warp or transverse wires around the line-wire, when by a further rotary movement of the main machine the roller 18 is caused to encounter the track-section 20, whereby the head 15 is moved outwardly and the needle withdrawn from the longitudinal wire, so as to enable the shuttle to move to the succeeding wire.

Upon the ends of the telescopic needle, as shown more clearly in Fig. 2, are the spools 22, which receive the coiled-wire bobbins 23, which form the transverse or woof strands of the fabric and which by the travel of the shuttle and the rotation of the needle are wrapped successively about the warp-wires in the formation of the woven fabric, said coiled cross-strands paying off of the spools from the needle as they are woven into the fabric by the travel of the shuttle and the operation of the needle.

The needle is rotated to wrap the bobbin-wires upon the longitudinal wires by means of a longitudinally-reciprocatory rack 24, which extends transversely of the machine and is pivotally connected, as shown at 25, to one end of a pitman 26, the opposite end of said pitman being attached to a crank 27 upon a shaft 28, carrying a pinion 29, adapted to mesh with a stationary rack 30. As the machine revolves said pinion is turned by 65 engagement with said rack, imparting a ro-

tary movement to the crank and reciprocating the rack 24, which in its movement in one direction is in engagement with the slotted pinion 31 on the needle-shaft, causing the needle to rotate when embracing the longitudinal wire and lying in the notches 21 of the track members. As the needle is retracted through the operation of the sliding head 15 it is raised or withdrawn from the notches, thereby carrying it from the longitudinal wire and removing its pinion from engagement with the rack 31, so that it will cease to rotate and that upon a movement of said rack it is not actuated. The forward movement of the rack-bar 24 occurs at the 80 moment the needle embraces each of the line-wires in succession and carries its pinion into contact with said bar.

To provide for a longitudinal reciprocation of the telescopic needle, there is mounted upon the female portion of the needle a slotted collar 32, within which the needle-shaft may rotate, but through which said shaft cannot move longitudinally. Extending from said collar is an arm 33, which stands parallel with the needle-shaft. In like manner a slotted collar 34 embraces the female portion 9 of the needle-shaft and is provided with the arm 35, which stands approximately parallel to the arm 33. In each of said arms is a pin 36, which is adapted to enter the slots 37 in the opposite faces of the collar 38, fixed to the shaft 39, whose outwardly-extending end carries a crank 40, provided at its free end with an antifriction-roller 41. It will be seen on referring to the dotted lines shown in Fig. 8 that a movement of said crank will rotate the collar 38 and actuate the arms 33 and 35, respectively, to impart a longitudinal movement to the male and female members of the needle, thereby elongating said needle, and that a movement of said crank in the opposite direction will contract the needle by causing the members thereof to slide together. This longitudinal reciprocation of the telescopic members of the needle is accomplished by means of the zigzag track 42, which is located in the path of the antifriction-roller 41 on the crank 40 and is so positioned as to engage said roller at the time the needle has made two revolutions around the line-wire and wrapped the transverse wire twice therearound, when by the elongation of said needle, due to the engagement of the roller of the crank in said zigzag track, will cause the third wrap to cross the other two, as shown at 43 in Fig. 7, thereby rendering the wrap or tie 44 perfectly secure and preventing it from becoming loose upon the longitudinal wire 6. There will be one of these zigzag tracks for each of the longitudinal or warp wires of the fabric, so that as the shuttle passes across the machine during the rotary movement thereof each of said tracks in succession will actuate the crank at the 130

proper time to elongate the needle and cause the formation of the cross-wrap, as before explained. By this arrangement two of the transverse strands are simultaneously woven 5 into the fabric during the passage of the shuttle across the machine, and at each winding of the cross-wires around the longitudinal wires the telescopic parts of the needle are actuated to form the cross-wrap 43, as illustrated in Fig. 7, producing in a rapid manner a woven fabric of superior quality.

At the initial point of operation as each shuttle enters upon its passage across the machine the ends of the transverse wires 15 carried in the form of bobbins are fastened to the selvage of marginal wire of the fabric by means of the rotary heads 45, which are mounted upon a common shaft and are operated by means of a reciprocatory rack 46 in 20 a manner fully set forth in my application referred to above, and as such operation forms no part of this invention it need not be further explained herein.

For the purpose of locking the rotary duplex needle to hold it in the proper position when it is withdrawn from a line-wire after the operation of wrapping the cross-wires thereon a spring-detent 47 is employed, which is mounted upon the hanger 14 and is 30 provided with a hook-shape end, which normally engages in the teeth of the pinion 31 to hold said pinion from rotating. In order to free the pinion so as to permit the needle to revolve when it moves into position upon a 35 longitudinal wire, said spring is caused to strike upon the track 3, so as to free it from engagement with said pinion, as clearly shown in Fig. 2.

Having thus fully set forth my invention, 40 what I claim as new, and desire to secure by Letters Patent, is—

1. In a machine for the manufacture of wire fabric, a longitudinally-slotted needle mounted to rotate, having longitudinally-reciprocal end portions, and means for reciprocating said end portions, during the rotary movement of the needle.

2. In a machine for making wire fabric, a longitudinally-slotted duplex needle, having 50 movable end portions adapted to carry the cross-wires, means for rotating said needle

and means for moving the end portions longitudinally during said rotary movement.

3. In a machine for making wire fabric, a rotary slotted needle adapted to embrace 55 the longitudinal wires, comprising telescopic members, each member being adapted to carry a cross-wire and wrap said cross-wire around the longitudinal wire, means for rotating said needle, and means for moving the 60 telescopic members thereof longitudinally in opposite directions during said rotary movement.

4. In a machine for making wire fabric, the combination of a movable shuttle, a rotary needle mounted in the shuttle having a longitudinal slot therein adapted to embrace the longitudinal wires, said needle comprising two sections, each of said sections having means for carrying a transverse wire, 65 means for rotating said needle and means for elongating and contracting the needle during said rotary movement.

5. In a machine for making wire fabric, the combination of a shuttle adapted to travel 75 across the machine, a longitudinally-slotted needle adapted to rotate in said shuttle and to successively embrace the longitudinal wires, said needle comprising slidable sections, each of which is adapted to carry a transverse wire, 80 means for rotating the needle intermittently and means for sliding said sections longitudinally during said rotary movement.

6. In a machine for making wire fabric, the combination of a movable shuttle, a slide- 85 able head mounted on said shuttle, a needle journaled in said head and having a longitudinal slot therein, said needle being formed of slidable sections, each of which is adapted to carry a cross-wire, means for reciprocating 90 said head intermittently, means for imparting an intermittent rotation to the needle, and means for simultaneously sliding the sections of the needle in opposite directions during the rotary movement thereof.

In testimony whereof I sign this specification in the presence of two witnesses.

GEORGE A. RAYMOND.
